(57) **CLAIM**

The ornamental design for an archery bow stand, as shown and described.

DESCRIPTION

FIG. 1 is an isometric view of an archery bow stand, showing our new design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken line in the figure drawings represents unclaimed portion of the design only and forms no part of the claim.
